SPRAY DISPENSING PUMP HEAD

Douglas F. Corsette, Los Angeles, Calif., assignor to The Drackett Company, Cincinnati, Ohio, a corporation of Ohio

Filed July 21, 1961, Ser. No. 66,019

Term of patent 14 years

(Cl. D62—2)

FIG. 1

FIG. 2

I claim:

The ornamental design for a spray dispensing pump head, substantially as shown.
